UNITED STATES PATENT OFFICE.

PERCY LLOYD FORBES, OF WEST MIDDLESEX, PENNSYLVANIA.

HAY-DISTRIBUTING APPARATUS.

1,216,558.

Specification of Letters Patent. Patented Feb. 20, 1917.

Application filed October 25, 1916. Serial No. 127,598.

To all whom it may concern:

Be it known that I, PERCY LLOYD FORBES, a citizen of the United States, residing at West Middlesex, in the county of Mercer and State of Pennsylvania, have invented an Improvement in Hay-Distributing Apparatus; and I do hereby testify that the following is a complete and concise description of the aforesaid hay-distributing apparatus as attested by the annexed figures and drawings, which are a part of these specifications.

My invention pertains to an improvement in hay-distributing apparatus, and is directed to the distribution of hay, straw or grain to any part of a mow by means of a switch, inclined tracks and friction rail attached thereto, in combination with any standard design of hay-carriers with forks 20 or slings.

One of the objects of my invention is the provision of a simple, but efficient switch whereby the car may be directed from the main horizontal track to side tracks located 25 at suitable points along the roof of the building in which it is installed. A further object of my improvement resides in the arrangement on the side track of means for returning the car to the main or horizontal 30 track after the load has been released. A third object of my improvements is located in a friction rail to prevent the too rapid descent of the car, and operating in conjunction with the descent of the car, the friction 35 produced being in proportion to the weight of the burden attached thereto.

Further objects and purposes of my invention will appear from an inspection of the drawings, the specifications describing 40 the same, and the claims appended thereto in which are set forth the arrangement of parts, combinations of elements, and novel structural details properly comprised within the scope of the same.

These objects I attain by means of the apparatus illustrated in the accompanying drawings in which—

Figure 1 represents a perspective view of the apparatus in operation. Fig. 2 is a cross-sectional view of switch and longitudinal view of the inclined tracks. In Fig. 3, the inclined friction rail is shown in a horizontal position. Fig. 4 is a transverse sectional view showing carriage in operation upon friction rail. Fig. 5 is a top view of switch. Fig. 6 represents a longitudinal

sectional view of switch, showing operation of locking head and hinge. Fig. 7 is a cross-sectional view embodying a detailed representation of the switch locking device, by 60 operation of which the car is conducted over any of the switches.

Referring now to the several figures of my invention in which like reference characters designate like parts, 1 is a view of the main track which can be constructed of angle or T iron conforming in size to the requirements of any standard design of car adapted to be conveyed thereover, is supported by hangers suspended from the rafters of the barn in which it may be installed, and is joined to the switch 24 at the switch hinge 2. 3 is the switch bolt acting in the double capacity of track hanger and switch support. By means of the reinforcing bar 70 4, I have secured the stability of the switch and, furthermore, have made possible the construction of the same within a space hitherto insufficient.

The locking head 6 is slidably mounted 80 upon the switch support 9 constructed with a slot which locking head slides horizontally along the said switch support, thus joining the switch to any track desired. 7 is the locking pin which moves vertically through 85 the locking head and switch support 9 at any one of the three apertures in the support 9, and, when the said locking head and switch support aline, joins the switch to any of the tracks desired by the operator. By 90 applying a downward pressure upon either of the switch-shifting ropes 30, the operator of my invention can, with little effort, neutralize the force of the spring 8 and, by means of the locking pin control arm 11, 95 raise the locking pin 7 from its position in any of the apertures in the switch support 9, thus rendering the said locking head 6 slidably adjustable to another track. After the locking pin 7 has reached the highest 100 point in its vertical movement, by continued pressure on either of the switch-shifting ropes 30, the locking head 6 is moved either to the right or left until the apertures are in alinement, when the spring 8 forces the locking pin 7 into the aperture in the switch support 9, the conjunction of the said locking head with the switch support 9 is accomplished, and the apparatus is now in proper adjustment for the operation of the car 110 thereover. In case the pressure on rope 30 should prove insufficient to move the lock-

ing head from its position, then, assisted by a pull rope 13 as shown, the combination of effort brings the locking head easily into alignment with the track desired.

- 5 When the loaded car 18 has traversed the inclined track 26, and when the buffer 28 has come to rest against the buffer spring 14, the empty car and fork 18, suddenly released from their burden, are drawn upward 10 along the inclined track 26 by the effect of the counterweight 27 operating by a rope attached to the car 18. The counterweight pulleys 10 serve to guide the car 18 around the curve in the inclined track 26 by insuring a pull nearly parallel with the track 26, instead of a sidewise pull on the car 18 as would occur without the aid of the pulleys. 15 My object in having a friction rail 21, as hereinbefore stated, is to prevent a too rapid descent of the loaded car 18 along the inclined track 26, which is bolted to the rafters. The operation of the friction rail 21 is embodied in the following description:—
- The loaded car 18 travels downward along 25 the inclined track 26, steadily gaining momentum; the weight of the car 18 with its burden causes the inclined track to drop slightly on the spring 16, which is secured to track adjusting bolt 29 by a nut 17; the 30 sag of the track causes the projection 22, which is bolted on the car frame 18 by bolt 20, to contact with the thrust on the friction rail 21, riveted to friction rail supporting bracket 15, thus checking the momentum of 35 the car and preventing its too rapid descent. At the release of the burden from the car, the spring 16 restores the track 26 to its normal position, all friction is obviated between the projection 22 and the friction rail 21, 40 and the car is free to be drawn up the inclined track 26 by the counterweight 27 operating around the counterweight pulleys 10, as hereinbefore described.

I am aware that prior to my invention 45 hay-distributing apparatus has been made

for operation of a car over a single straight horizontal track, distributing its burden only in that part of the mow directly underneath the said straight track; but I claim that my invention is novel in utilizing a 50 switch in combination with curved inclined side tracks, with a friction rail attached thereto, which enables the burden to be distributed at points underneath either the inclined side tracks or the straight horizontal 55 track.

Having now described my invention in detail, what I claim, and desire to secure by Letters Patent is:—

1. An improvement in hay-distributing apparatus, having the combination of curved inclined tracks at either side of straight horizontal track, and a friction rail attached thereto, which insures uniformity in rate of descent of a loaded car. 60
2. An improvement in hay-distributing apparatus, having the combination of curved inclined tracks, a friction rail attached thereto, and means for returning unburdened car along the curved inclined tracks 70 to the main horizontal track, accomplished by a counterweight coöoperating with counterweight pulleys, substantially as described. 65
3. The combination, in an improvement in, hay-distributing apparatus, of curved 75 inclined side tracks, a friction rail attached thereto, and a switch for directing a car from the horizontal track to the side tracks, the switch being provided with a locking device which firmly joins said switch to any 80 selected track, and operated by means of ropes which render the switch slidably adjustable to any track desired. 85

In testimony that the above specifications are correct, I have hereunto affixed my signature in the presence of two witnesses.

PERCY LLOYD FORBES.
